UNITED STATES PATENT OFFICE.

EARL G. SMITH, OF CRANDON, WISCONSIN.

VALVE-CONTROL MECHANISM.

1,347,300.

Specification of Letters Patent. Patented July 20, 1920.

Application filed September 19, 1919. Serial No. 324,746.

To all whom it may concern:

Be it known that I, EARL G. SMITH, a citizen of the United States, residing at Crandon, in the county of Forest, State of Wisconsin, have invented a new and useful Valve-Control Mechanism; and I do hereby declare the following to be a full, clear, and exact description of the invention, such as will enable others skilled in the art to which it appertains to make and use the same.

The invention relates to valve control mechanism for internal combustion engines and has for its object to provide cam means for operating a lever which lever controls the exhaust and ignition so that said engine may be operated to the right or to the left.

A further object is to provide a valve and ignition control lever which may be shifted from one cam to another thereby reversing the engine. Also to provide gear means operative by the crank shaft for revolving the cam thereby operating the control lever.

A further object is to provide the control lever with a pivoted member having on its free end a roller adapted to be rotated by the cams and prevent friction between the cams and the lever and to provide a pivoted lever for actuating the shifting from one cam to the other.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:—

Figure 1 is a side elevation of the valve controlling mechanism.

Fig. 2 is a plan view of a portion of the cam gear and the end of the pivoted lever, parts being broken away to better show the structure.

Fig. 3 is a detail view of the cam gear.

Fig. 4 is a vertical sectional view through the cam gear.

Referring to the drawings, the numeral 1 designates a fly wheel carried by a crank shaft 2 of an internal combustion engine and 3 a cam gear which meshes with a gear 4 secured to the crank shaft 2. Cam gear 3 is rotatably mounted in a bearing 5 of a bracket 6 which may be secured to the engine base or to any other suitable support.

The outer face of the cam gear 3 is provided with cams 7 and 8 which are preferably formed integral with the cam gear and with each other. Cams 7 and 8 are at 60 right angles to each other and their longitudinal axis being at about 90 degrees from each other. Cam 7 is the cam which normally operates the valve and ignition spark, that is, when the engine is turning to the 65 right and cam 8 is the cam which is utilized for operating the exhaust valve and ignition spark when the engine is turning to the left.

Slidably mounted in a bearing 9 which may be carried by the engine casing or supported in any other manner is a valve rod 10, which controls the exhaust valve of the engine, said valve rod also having pivotally connected thereto as at 11, a rod 12, which controls the spark. The lower end of the 75 lever 10 has pivoted thereto as at 13 a lever 14, which lever 14 is provided with a roller 15 on its lower ends, said roller being adapted to engage the camming surfaces of the cams 7 and 8 thereby operating the exhaust 80 valve and the ignition spark. When the roller 15 is in engagement with the cam 7, the valve rod 10 and rod 12 which controls the ignition spark will so operate as to work the spark and exhaust valve so that the engine 85 will turn to the right. When it is desired to reverse the engine, that is cause the same to turn to the left, pivoted lever 14 is shifted laterally until the roller 15 engages the camming surface of the cam 8 thereby changing 90 the position of the valve rod 10 and ignition rod 12, so that the cam 8 as it revolves in the opposite direction will cause the engine to turn to the left. It is to be understood that

the type of engine to which the mechanism is applied has an automatically controlled intake valve. The shifting of the pivoted lever 14 is done by a lever 16, the lower end of which is pivoted as at 17 to a bracket 18 carried by the engine base or in any other 100 suitable position. Lever 16 is provided with a yoke 19, which engages the pivoted lever 14 so that said pivoted lever may be moved from engagement with the cam 7 to engagement with the cam 8. When the roller 15 is 105 in engagement with the cam 7 a detent 20, slidably mounted in a bearing 21 carried by the lever 16 is in engagement with a notch 22 in a segment 23 carried by the bracket 18. Detent 20, when it is desired to shift the 110 roller 15 to the cam 8, is raised and the lever 16 moved outwardly until the detent 20

drops into engagement with the notch 24 of the segment 23 thereby securely holding the roller in proper alignment with the cam 8.

Valve rod 10 is normally under tension of 5 a spring 25, which spring will cause the roller 15 to remain in engagement with the cams 7 and 8 so that said roller will normally follow the camming surfaces of the cam. However, spring 25 may be located in any 10 other convenient location, or when the exhaust rod 10 is connected directly to the exhaust valve which exhaust valve is normally closed by a valve spring, the spring 25 may be eliminated and the valve spring utilized 15 for maintaining the roller 15 in engagement with the cams 7 and 8.

Bearing 9 is a loose bearing and transversely is of considerably greater width than the width of the push rod so that the movement 20 of the pivoted lever 14 from one cam to the other may be accomplished.

From the above it will be seen that a shifting mechanism is provided whereby the reversing of the engine may be accomplished 25 quickly and one wherein cams are utilized for operating the exhaust and ignition when the engine is turning to the right or turning to the left.

The invention having been set forth what 30 is claimed as new and useful is:—

1. A reversing mechanism for internal combustion engines comprising an exhaust control rod and an ignition control rod, a pair of cams operated by the crank shaft, 35 one of said cams being adapted to operate the valve and ignition control rods for turning the engine to the right, the other cam being adapted to operate the exhaust valve control rod and the ignition control rod so as 40 to operate the engine to the left and means whereby the operating valve rod may be shifted from one cam to the other.

2. A reversing mechanism for internal combustion engines comprising an exhaust 45 control rod and an ignition control rod connected thereto, said exhaust control rod being slideable in a bearing, the lower end of said exhaust control rod having a lever pivoted thereto, a cam gear meshing with a gear 50 on the crank shaft, said cam gear being pro-

vided with a pair of cams, one of said cams being adapted to reciprocate the exhaust control rod so that the engine will turn to the right, the other cam being adapted to operate the exhaust valve control rod 55 so that the engine will turn to the left, a lever connected to the pivoted lever whereby the end of said pivoted lever may be moved from engagement with one of the cams and into engagement with the other 60 and means whereby the pivoted lever may be locked in engagement with either of the cams.

3. A reversing mechanism for internal combustion engines comprising an exhaust 65 control rod and an ignition control rod connected thereto, said exhaust control rod being slideable in a transversely enlarged bearing, the lower end of said exhaust control rod having a lever pivoted thereto, a cam 70 gear meshing with a gear on the crank shaft of the engine, said cam gear being provided with a pair of cams at 90 degrees from each other, one of said cams being adapted to reciprocate the exhaust control rod and its ignition control rod for operating the engine 75 so that its crank will turn toward the right, the other cam being adapted to operate the valve control rod and the ignition control rod so that the engine will turn to the left, 80 the pivoted lever having its lower end a roller adapted to be placed in engagement with the cams of the cam gear, a transversely pivoted lever connected to the pivoted lever, said transversely pivoted lever forming 85 means whereby the pivoted lever may be shifted from one cam face to the other and detent means carried by the transversely pivoted lever whereby said lever may be locked so that roller at the end of the pivoted lever 90 may be locked into engagement with the cam faces.

In testimony whereof I have signed my name to this specification in the presence of two subscribing witnesses.

EARL G. SMITH.
